UNITED STATES PATENT OFFICE.

WILLIAM E. DE VOE, OF CHICAGO HEIGHTS, ILLINOIS, ASSIGNEE TO EDWARD H. FALLOWS,
TRUSTEE, OF NEW YORK, N. Y.

Brake-Shoe.

No. 874,663.

Specification of Letters Patent.

Patented Dec. 24, 1907.

Application filed July 17, 1907. Serial No. 384,154.

To all whom it may concern:

Be it known that I, WILLIAM E. DE VOE, a citizen of the United States, and a resident of Chicago Heights, in the county of Cook and State of Illinois, have made and invented 5 certain new and useful Improvements in Brake-Shoes, of which the following is a specification.

My invention relates to an improvement in 10 brake shoes for use upon the wheels of railway cars and locomotives, and more particularly to that kind or type thereof which are generally used upon the driving wheels of engines, such shoes being usually formed 15 with a wheel face to contact with the tread of the wheel, and a curved flange to contact with the flange of the wheel. Shoes of this character have heretofore been constructed either entirely of cast iron or of cast iron 20 having a steel plate applied at or adjacent to the back thereof. It has been found, however, that those shoes made entirely of cast iron, are structurally weak, in that the attaching lug made integral with the body, 25 frequently breaks either in service, or in handling, especially when the metal of the shoe is of hard or chilling iron. In order to overcome this inherent defect in cast iron shoes and avoid the danger of the shoe be- 30 coming detached from the brake head, by reason of the breakage of the attaching lug, it has become the custom to reinforce the lug with a strip or strap of steel, the ends of 35 the steel lug being anchored in the body metal of the shoe, and in those instances where the shoe is provided with a steel back, the ends of the lug have been anchored under the back. While this strengthening or reinforcing of a cast metal lug by a wrought 40 metal or steel lug, materially strengthens the same, yet it is open to some objections, in that the projecting ends of the steel lug embedded in the body of the shoe below the steel back, at times cut or injure the tread of 45 the wheel after the shoe has been worn down in service. In other instances, the projecting ends of the steel lug containing as they do, a small amount of metal, are burned or injured by the molten cast iron in which 50 they are embedded, sometimes resulting in the formation of blow-holes in the body of the shoe. Again, when the body of the shoe has been worn down in service, it sometimes happens that the ends of the lug projecting 55 below the steel back, are also worn away,

thereby materially decreasing the strength of the lug and rendering it liable to be detached entirely from the shoe.

The object of my present invention is to provide an engine driver shoe with a steel 60 back, wherein the lug shall be made integral with the latter, and reinforcing the cast metal lug, or itself reinforced by the cast metal flowing wholly or partially around the same, so that all danger of the lug being 65 broken or becoming detached from the shoe, or destroyed or injured when the shoe is worn down in service, will be entirely overcome.

With these and other ends in view, the invention consists in certain novel features of construction, as will be hereinafter fully described and pointed out in the claims.

In the accompanying drawings Figure 1 is a view in perspective of my improved steel 75 back. Fig. 2 is a transverse section thereof taken on the line 2—2 of Fig. 1. Fig. 3 is a top plan view of the same. Fig. 4 is a sectional view of the plate taken on the line 4—4 of Fig. 3, and applied to the body of the 80 shoe. Fig. 5 is a transverse section of the shoe having the back applied to the body. Fig. 6 is a similar view of a modified form of the back. Fig. 7 is a perspective view of a modified form of one end of the plate. Fig. 85 8 is a cross sectional view thereof after the lug is struck up; and Fig. 9 is a similar view showing the end of the plate as applied to the body of the shoe.

In practice I employ a plate A of steel, or 90 other tough metal, curved in its length to conform to the curvature of the body of the shoe and also curved transversely along one side to conform to the curvature of the flange of the shoe, as illustrated at F. In order to 95 secure the required strength and prevent damage or injury to the lug as the shoe is worn down in service, I form two transverse slots D across the tread portion of the plate and near the center thereof, these slots ex- 100 tending into the curved portion F of the plate, or instead of slotting the plate it may be slotted. The metal strip or strap E lying between these slits or slots is then forced up- 105 wardly, as clearly illustrated in Fig. 1 of the drawing, to the required height for forming the key-lug or reinforcing the cast metal thereof, one end of the strip or strap E being integral with the curved flange F and the other end integral with the tread portion A. 110

This strip may be extended straight across from the flange, as illustrated in Fig. 5, having approximately the same height thereof, or it may be lowered or curved, as illustrated in Fig. 6 in order that the body metal C may flow over the same to assist in securely anchoring it in place, the strip E itself forming the top wall of the key-way D, the cast metal of the body C forming the sides and bottom thereof.

It will of course be understood without further description or illustration that the metal of the body C may be allowed to flow entirely around the strip E, the latter thus forming a reinforce for the cast metal lug; or again, I may omit flowing the cast iron under or above the wrought metal strip, which in itself is sufficiently strong to hold the head and shoe together.

20 By means of this construction of lug it will be understood that all danger of its becoming worn, damaged or destroyed in the event of the shoe being worn down to and into the steel back, is obviated. Furthermore, the 25 shoe is provided at its middle portion with a free ventage, and with little or no danger of blow holes being caused by burning the wrought iron lug, which has heretofore been the case. As illustrated in the drawings, the 30 back is also provided with the openings B, both in the tread portion A and curved flange F, in order to allow the cast metal of the body to flow through the same and securely anchor said back to the body C of the shoe.

35 As is well known, some shoes, particularly in those used on the driver wheels of engines or locomotives, the central key-lug is omitted, one end of the shoe being secured by means of a bolt, and the opposite end provided with a hook, under which latter the brake head rests. In such instance, I prefer to form the end of the plate as illustrated in Figs. 7, 8 and 9, wherein it is shown as provided with the slot G extending from about the top of the flange F to within a short distance of the outer edge of the tread portion A¹, the metal between said slot and end of the plate being struck upwardly in order to form the hook H, as illustrated in Fig. 8, the cast 40 metal of the body C¹ flowing up through the opening and reinforcing said hook, as illustrated at c¹ (Fig. 9). If desired, an opening c² may also be formed in the end of the plate to allow the cast metal to flow up through 45 the same, as illustrated at c³ (Fig. 9), in order to assist in anchoring the back to the body 50

and reinforce the rear side of said hook. Or if desired, in those instances wherein the attaching lug is formed at about the center of the plate, a strip may be forced up at the 60 end, as described, in order to reinforce the end stops, in all of which instances the strip forms an integral part of the steel back and reinforces either the key-lug or end stops and preserves the integrity between the back and 65 attaching point until the body metal has been completely worn away.

Having fully described my invention, what I claim as new and desire to secure by Letters Patent, is:—

1. A back for a brake shoe formed with a flange and tread portions, and a reinforcing strip formed partially from each, substantially as described.
2. A back for a brake shoe formed with a 70 flange and tread portions, and a reinforcing strip struck up from the metal of said flange and tread portions, substantially as described.
3. A back for a brake shoe formed with a 75 flange and tread portions, and a reinforcing strip, one end of said strip being connected with said flange and the other with said tread portion, substantially as described.
4. A back for a brake shoe formed with a 80 flange and tread portions, and an integral reinforcing strip, one end being integral with said flange and the other with said tread portion, substantially as described.
5. A back for a brake shoe formed with a 85 flange and tread portions, and a key-lug formed partly of the metal of said flange and partly of the tread portion, substantially as described.
6. A back for a brake shoe formed with a 90 flange and tread portions, and an integral key-lug of approximately the height of said flange, substantially as described.
7. A back for a brake shoe formed with a 95 flange and tread portions, and an integral lug 100 formed partly of the metal of said flange and partly of the metal of said tread portion, and having approximately the height of said flange portion, substantially as described.

Signed at Chicago, in the county of Cook, 105 and State of Illinois, this 12th day of July A. D. 1907.

WILLIAM E. DE VOE.
